UNITED STATES PATENT OFFICE.

LEE C. SHARP, OF PLATTSMOUTH, NEBRASKA, ASSIGNOR TO AMERICAN CAN COMPANY, OF NEW YORK, N. Y., A CORPORATION OF NEW JERSEY.

CAN-HEADING MACHINE.

1,082,562.

Specification of Letters Patent. Patented Dec. 30, 1913.

Application filed April 1, 1909. Serial No. 487,291.

To all whom it may concern:

Be it known that I, LEE C. SHARP, of Plattsouth, county of Cass, State of Nebraska, have invented certain new and useful

5 Improvements in Can-Heading Machines, of which the following is a full, clear, and exact specification, such as will enable others skilled in the art to which it pertains to make and use the same.

10 My invention relates to can heading machines.

One object is to provide a machine adapted to attach the heads or covers to the bodies of cans, and particularly to those machines in which the flanged edges of the covers are doubled seamed on the ends of the bodies to render a can hermetically sealed without the employment of solder.

Another object of the invention resides in 20 the provision of a can heading machine embodying such characteristics that the operation of the can heading mechanism is practically unobstructed so that the operator of the machine may readily see the work being performed thereby, the present machine embodying preferably a plurality of heading mechanisms operating simultaneously.

Another object resides in the provision of 30 an automatically operating can heading machine embodying a reciprocating straight line feeding means carrying elements adapted to engage the cans during the forward movement of the feeding means and shift them step by step in one direction, with the can engaging means constructed for operation upon movement of the feeding means in 35 a reverse direction to pass the cans and not move them in said reverse movement or interfere with the positioning of any of the 40 cans on the feeding means.

A still further object resides in the provision of a can heading machine embodying a vertically reciprocating table and a horizontally reciprocating feeding means adapted 45 to transport the cans through the machine in one direction, heading one or more cans during the feed thereof without the employment of solder and without rotating the cans, the functions of the present machine 50 being performed through the instrumentality of a comparatively simple mechanism designed to reduce excessive relative speeds of the revolving members thereof and to afford a simple and less dangerous method of introducing the cans and parts to the feed-

way, all for the purpose of providing a rapid and more efficient machine for executing the work than the machines now employed for the purpose.

It is still further designed to provide a can 60 heading machine embodying means to feed the cans and parts thereof through the machine in relation to the can heading mechanism without danger of lateral or other accidental displacement of the cans transported by the feeding means, the means for preventing such accidental displacement of the cans being preferably adjustable for the accommodation of can bodies of different diameters.

With the above and other objects in view, the present invention consists in the combination and arrangement of parts hereinafter more fully described, illustrated in the accompanying drawings, and particularly 70 pointed out in the appended claims, it being understood that changes may be made in the form, proportion, size and minor details without departing from the spirit or sacrificing any of the advantages of the invention.

In the drawings:—Figure 1 is a side elevation of the invention. Fig. 2 is a front elevation thereof. Fig. 3 is an enlarged detail view illustrating a portion of the reciprocating table, the straight-line feeding means, and particularly the means for guiding the cans over the table. Fig. 4 is an enlarged detail sectional view illustrating a portion of the can heading mechanism including particularly the means for operating the can heading mechanism. Fig. 5 is a longitudinal sectional view of a portion of the feed bar illustrating the spring controlled can engaging dogs.

Referring now more particularly to the accompanying drawings, there is shown a supporting frame including a column 1, which is provided with a guide-way 5, arms 2 and 4, upon which latter is mounted the supporting parts 3 and 4, there being a drive shaft 6 journaled and supported in the arm 2 and the column 1, and at its outer end provided with the tight and loose pulleys 10 and 11, respectively, to provide for the rotation of the drive shaft 6 in any suitable manner, and from any suitable source (not shown).

The character 17 indicates a table provided with a leg 7 adapted to slidably em-

brace the guide 5 on the column 1 so that the table may be reciprocated vertically in a manner hereinafter described. This table is provided with a longitudinal groove *q*, 5 along opposite sides of which are shoulders *r* upon which rest the pair of cleats *s* adapted to overlap the preferably reduced edges *t* of the feed-bar 16 mounted in the aforesaid groove *q*, the can bodies 19 being adapted to 10 rest upon the cleats *s* or any other part of the table 17 directly over the feed-bar 16, and as the cans fed through the machine are of various diameters, I render the feed-way formed by the bars 38 adjustable by mounting the bars 38 so that they are movable toward and from each other, each guide-way bar 38 being preferably notched to provide a shoulder *u* adapted to overlap the lower seam *v* of the can bodies 19 to prevent accidental forward movement of the bodies 19 out of the guide-way and also to positively prevent lateral displacement of the can bodies. These guide-way bars 38 are preferably held in adjusted relation to provide 25 various widths of feed-ways by means of the clamping elements *w* secured on the table 17 by means of the bolts or other suitable fastenings *y*.

The feeding means consists preferably of 30 a bar which is adapted to be reciprocated horizontally on the table 17, the latter being reciprocal at a direct right angle to the reciprocation of the feed-bar. The feed-bar is preferably provided with a plurality of 35 spaced openings 17', one end of each opening having an inwardly directed inclined shoulder 17^a designed for coöperation with the inclined edge 17^b of the can engaging dog 17^c pivoted at 17^d within the opening 40 17', with its inclined edge 17^b held normally in engagement with the shoulder 17^a through the instrumentality of a spring or equivalent 17^e, secured at one of its ends to the underside of the dog 17^c and at its opposite 45 end bearing upon a pin shoulder or the like 17^f. These dogs 17^c are adapted to engage the can bodies 19 when the feed bar is moved in one direction, as will be hereinafter explained, and to be depressed into the openings 17' when the feed-bar is moved in the opposite direction, so that upon the reverse movement of the feed-bar, the dogs 17^c will 50 not dislodge or in any way interfere with the positions of the respective cans, by which 55 latter the dogs are depressed as they pass beneath the latter.

To reciprocate the feed-bar a rod 12 is connected at one end to the eccentric 9 and at its opposite end pivotally connected to 60 the lever 13 fixedly secured upon one end of the rock shaft *b*, secured to and movable with the table 17, the rock shaft having connected to its opposite end a lever 14 which is pivotally connected to one end of 65 the link 15, whose opposite end is pivotally

mounted in the lug *c* on the underside of the reciprocating feed-bar 16, there being a slot *d* in the table 17, through which the lug *c* depends from the feed-bar and by virtue of which slot reciprocation of the feed-bar on the table is permitted when the drive shaft is driven, and the connections between the drive shaft and feed-bar consequently operated. By virtue of the connection of the rock shaft *b* to the table 17, the feed-bar is 70 moved with the table in the vertical reciprocation of the latter.

To vertically reciprocate the table 17, a rod 20 is connected at one end to the cam 8 on the drive shaft 6 and at its opposite end pivoted to a rod 21, which in turn is pivoted to one end of a lever 22 fulcrumed on the lug 23 on the column 1, the opposite end of the lever 22 being provided with a cup *z* in which is disposed a ball 25 rotatably mounted on a screw 27, which passes through the cup *z* and at its upper end is pivotally connected to the lugs *e* on the leg *f* of the table 17. By operation of the hand wheel 26, the parts between the leg *f* of the table 17 and the drive shaft 6 may be adjusted, and upon operation of the cam 8 on the drive shaft 6, the table is reciprocated vertically on the guide 5 by virtue of the said connections between the drive shaft and the table. 85

The cam 7 on the drive shaft 6 has connected with it a shaft 28, which is mounted in the part 3 of the frame and which has its upper end screw threaded to receive the adjusting nuts 28' between which one end of the lever 29 fits and by which said end of the lever 29 may be adjusted. The lever 29 is fulcrumed at *g* upon the post *h* and at its opposite end it has a T-bar 29', whose ends fit between the clamping nuts 30' on the screw threaded upper ends of the reciprocating rods 30, which latter have sliding movement in the pulley spindles 31, the lower ends of the rods 30 each being provided with a pin *p* adapted to slide in the slots *i* in the corresponding spindles 31, the pins *p* having their ends fixedly secured in the corresponding collars 32, and by reciprocating movement of these collars, which is caused by the reciprocation of the reciprocating rods 30, together with the pin connection *p*, the double seaming levers 33, together with the double seaming rollers 34 attached thereto, are operated to open and close when the lever is running to effect a 100 seaming of the cover on the can body 19. The levers 33 are sustained in the pulleys 35 and are revolved therewith, they being mounted upon the pivot *j* on the pulleys 35, and at their upper ends having adjustable 105 elements, such as screws *m*, adapted to bear at their inner ends against the annular wedge *n* fixedly secured to the lower end of the split sleeve *o* mounted to rotate upon the collars 32. These elements *m* bear 110

ighly against the annular wedge members *n* so that as the pulleys 34 are rotated, the springs 33 will cause the inner ends of the elements *m* to tightly engage the members *n* and effect rotation of the sleeve *o* on the collars 32, and as the collars 32 are raised and lowered, as the result of reciprocation of the rods 30, the elements *m* rise up and down the cam faces of the wedge members *n*

10 to effect an opening and closing of the seaming elements or levers 33 upon their pivots *j*, as will be obvious, the operation of these seaming elements or levers 33 in their opening and closing operation being timed according to the reciprocation of the table and the reciprocation of the feed-bar.

The lower ends of the pulley spindles 31 are provided with chucks 39 which obviously do not revolve, but which enter the can head 20 and hold the can firmly upon the table and prevent the can from turning. These chucks coöperate with the table and the members 38 in preventing any movement of the can bodies 19 during the seaming operation.

It will now be understood that the cans receive two movements in their course through the machine, that is, an up and down movement and a horizontal movement 30 in a straight line under the seaming or operating devices.

In operation the machine is set in motion. The pulleys which carry the double seaming elements are caused to revolve by a belt 35 (not shown) which passes over the pulleys 36, pulleys 35 and idler pulley 37. The table, which sustains the cans and the feed-bar which moves them, work in unison with the double seaming rolls, which open and 40 close in proper relation thereto. The operator places a can with its loose cover on the table at the extreme right in Fig. 1. The pawl, dog, or finger 17 in the reciprocating feed-bar engages the can body at the proper 45 time, feeding it to the first set of rolls 34, where it receives an operation which in some cases may complete it, but in others it is carried to the next set of seaming elements, where it receives a second seaming operation. If necessary, other attachments may 50 be placed in the line of feed to perform other operations, for instance, filling devices to fill the cans, an automatic device for placing the covers, etc. After the receptacle receives its last operation, it is ejected by the last pawl or finger 17 into a receptacle at 55 the extreme left of the table.

Whenever a can is moved from the first seaming device to a second one for further 60 operation, it will be seen that two cans are being operated on simultaneously, thereby effecting a considerable saving in time over methods in which the cans must receive a plurality of operations separately. The 65 feed bar reciprocates horizontally while the

feed table reciprocates vertically, and also while the feed table is stationary during the seaming operation, the feed bar at this time making its backward stroke into position for feeding forward successive cans. There 70 can be no slopping of the contents of the cans or other receptacles incident to centrifugal action, because the cans do not revolve. In practical operation the horizontal movements of the cans to feed them successively one by one into registry with the seaming mechanism and the up and down movements to clamp them successively against the upper stationary chuck plate are not sufficient in extent or rapidity to cause 75 slopping of the contents even when the cans are filled with liquid materials. The operator is at a safe distance from the revolving elements of the machine, and all that is required of him is to place a can at the proper 80 station on the machine table. The cans are then fed through the machine automatically, receiving all operations necessary to seam and eject them automatically.

What is claimed is:—

1. In a can heading machine, a frame, a table mounted to reciprocate vertically on the frame, seaming heads mounted on the frame above the table, stationary chuck plates against which the cans are clamped by the upward movement of said table, a straight line feeding means mounted to reciprocate on and carried by said table, a drive shaft, a connection between the drive shaft and the table whereby the latter may 90 be reciprocated vertically, and a connection between the drive shaft and the feeding means whereby the latter may be reciprocated horizontally to effect a step by step movement of the cans forwardly in one 95 direction, the cans being fed from one head to the other during each reciprocation of the table.

2. In a can heading machine, a frame, a table mounted to reciprocate vertically on the frame, a plurality of seaming stations mounted on the frame above the table, stationary chuck plates against which the cans are clamped by the upward movement of said table, a feeding means mounted to 110 reciprocate horizontally on and carried by said table, means to reciprocate the table vertically, and means to reciprocate the feeding means horizontally to effect a step by step movement of the cans forwardly in 115 one direction, the cans being fed from one station to the other during each reciprocation of the table.

3. In a can heading machine, a frame, a table mounted to reciprocate vertically on the frame, a seaming means mounted on 125 the frame above the table, a stationary chuck plate against which the cans are clamped by the upward movement of said table, a straight line feeding means mounted to re- 130

4

5 ciprocate horizontally on and carried by the table during reciprocation of the latter and also when the table is at rest, means to reciprocate the table, and means to reciprocate the feeding means equally each reciprocation and to effect a step by step movement of the cans forwardly in one direction.

10 4. In a can heading machine, a frame, a table mounted to reciprocate vertically on the frame, a seaming means mounted on the frame above the table, a stationary chuck plate against which the cans are clamped by the upward movement of said table, a feeding means mounted to reciprocate on and carried by the table, means to reciprocate the table, and means to reciprocate the feeding means equally each reciprocation during reciprocation of the table and also when the latter is at rest.

15 5. In a can heading machine, a frame, a vertically movable frame mounted on the table, a seaming means mounted on the frame above the table, a stationary chuck plate against which the cans are clamped by the upward movement of said table; and a feeding means mounted to reciprocate horizontally on and carried by the table during movement of the latter and also when the latter is in its uppermost position.

20 6. In a can heading machine, a frame, a table movably mounted thereon, a seaming means mounted on the frame above the table, a stationary chuck plate against which the cans are clamped by the upward movement of said table, and a feed-bar mounted for reciprocation on and carried by the table, during movement of the latter and also when the latter is in its uppermost position.

25 7. In a can heading machine, a frame, a table mounted to reciprocate vertically on the frame, a seaming means mounted on the frame above the table, a stationary chuck plate against which the cans are clamped by the upward movement of said table, and a straight line feeding means mounted to reciprocate forward and backward during each complete up and down reciprocation of the table and carried by the table, substantially as specified.

30 8. In a can heading machine, a frame, a table mounted to reciprocate vertically on the frame, a seaming means mounted on the frame above the table, a stationary chuck plate against which the cans are clamped by the upward movement of said table, a horizontally reciprocating feed-bar carried by the table and mounted to move in one direction to shift the cans in the same direction, said feed-bar being operable to move in the opposite direction without moving the cans, one of these movements taking place during a movement of the table.

35 9. In a can heading machine, a frame, a table mounted to reciprocate vertically on

the frame, a seaming means mounted on the frame above the table, a stationary chuck plate against which the cans are clamped by the upward movement of said table, and a straight line feeding means mounted to reciprocate on and carried by the table and operable for movement in one direction on the table to shift the cans intermittently in one direction during the movement of the table, substantially as specified.

40 10. In a can heading machine, a frame, a table mounted to reciprocate vertically on the frame, a seaming means mounted on the frame above the table, a stationary chuck plate against which the cans are clamped by the upward movement of said table, and a straight line feeding means mounted to reciprocate on and carried by the table and operable for movement in one direction on the table to shift the cans intermittently in one direction during a movement of the table and also operable in the opposite direction beneath the cans without moving the latter.

45 11. A can heading machine, a frame, a table mounted to reciprocate vertically on the frame, a seaming means mounted on the frame above the table, a stationary chuck plate against which the cans are clamped by the upward movement of said table, a drive shaft, a connection between the drive shaft and table to reciprocate the latter, a straight-line feeding means mounted to reciprocate on and carried by the table and operable on the table to feed the cans through the machine between the seaming means and the table, means for reciprocating the feeding means while the table is in its uppermost position, spring controlled means mounted on the feeding means to engage the cans and move them with the feeding means when the latter reciprocates in one direction and depressible to pass under the cans when moved in the opposite direction so as not to shift the cans upon reverse movement of the feeding means.

50 12. In a can heading machine, a frame, a table mounted to reciprocate vertically on the frame, a seaming means mounted on the frame above the table, a stationary chuck plate against which the cans are clamped by the upward movement of said table, a straight line feeding means mounted to reciprocate horizontally on and carried by the table to feed the cans through the machine between the seaming head and the table, means for reciprocating the feeding means while the table is in its uppermost position, means mounted on the feeding means to engage the cans and move them with the feeding means when the latter reciprocates in one direction and being operable out of the path of the cans when moved in the opposite direction so as not to shift the cans upon reverse movement of the feeding means.

13. In a can heading machine, a frame, a table mounted to reciprocate vertically on the frame, a seaming means mounted on the frame above the table, a stationary chuck plate against which the cans are clamped by the upward movement of said table, a feed bar mounted to reciprocate on the table to feed the cans through the machine, said bar being moved in one direction while the table is in its uppermost position, elements carried by the feed bar for projection into engagement with the cans during movement of the feed bar in one direction and operable upon movement of the bar in the opposite direction to avoid moving the cans.

14. In a can heading machine, a frame, a table mounted to reciprocate vertically on the frame, seaming means above the table between which and the table the cans are clamped at the upward limit of movement of the table, a feeding means mounted to reciprocate horizontally on and carried by the table, means on the feeding means to engage the cans and feed them through the machine step by step as the table lowers and to snap under and pass the cans when the feeding means moves in the opposite direction at a time when the cans are clamped between the table and the seaming means.

15. In a can heading machine, a frame, a table mounted to reciprocate vertically on the frame, seaming heads above the table between which and the table the cans are held tightly at the upward limit of movement of the table, and a feed bar mounted to reciprocate horizontally on and carried by the table, means on the feed bar to engage the cans and feed them through the machine as the table lowers and to pass under the cans when the bar moves in the opposite direction.

16. In a can heading machine, a frame, a table mounted to reciprocate vertically on the frame, seaming heads above the table between which and the table the cans are held tightly at the upward limit of movement of the table, and a feed bar mounted to reciprocate horizontally on and carried by the table, means on the feed bar to engage the cans and feed them through the machine as the table lowers and to pass under the cans when the bar moves in the opposite direction, at a time when the cans are clamped between the table and the heading means.

17. In a can heading machine, a frame, a reciprocating table on the frame, a seaming means mounted on the frame above the table, a stationary chuck plate against which the cans are clamped by the upward movement of said table, a straight line feed way on the table, means for adjusting the width of the feed way, can stripping means carried by the table, and a feed-bar operable in the feed way to feed the cans intermittently therethrough, said feed bar reciprocating horizontally on the table and being carried up and down with the table.

18. In a can heading machine, a frame, a reciprocating table on the frame, a seaming means mounted on the frame above the table, a stationary chuck plate against which the cans are clamped by the upward movement of said table, a straight line feed way on the table, means for adjusting the width of the feed way, a feed-bar operable in the feed way to feed the cans intermittently therethrough, said feed bar reciprocating horizontally on the table and being carried up and down with the table, said bar being reciprocated in one direction while the table is in its uppermost position, and dogs on the feed bar operable automatically for movement into and out of engagement with the cans.

19. In a can heading machine, a frame, a vertically movable table on the frame, a stationary chuck plate against which the cans are clamped by the upward movement of said table, a seaming means on the frame, a feed bar mounted to slide in opposite directions on the table and carried thereby and having dogs operable for movement into and out of engagement with the cans to shift the latter in one direction when engaged therewith and to pass the cans, while the latter are clamped, upon movement of the feed bar in the opposite direction.

20. In a can heading machine, a vertically movable table provided with a groove, a feed bar mounted in the groove of the table for reciprocation therein, said feed bar being moved up and down with the table, the edges of the feed bar being reduced, bars fitted over the table and the edges of the feed bar for the support of the cans, and adjustable members mounted on the table to form a guide-way substantially equal in width to the diameter of the cans.

21. In a can heading machine, a vertically movable table provided with a groove, a feed bar mounted in the groove of the table for reciprocation therein, said feed bar being moved up and down with the table, the edges of the feed bar being reduced, bars fitted over the table and the edges of the feed bar for the support of the cans, and adjustable members mounted on the table to form a guide-way substantially equal in width to the diameter of the cans, the inner edges of said members being reduced to provide shoulders to overlap the lower seams on the cans.

22. In a can heading machine, a frame, a vertically movable table on the frame, a stationary chuck plate against which the cans are clamped by the upward movement of said table, means on the frame to seam the cans, the table having a groove, a feeding means mounted to reciprocate horizontally

tally on the table and carried thereby and operable in the groove, and guiding members on the frame upon opposite sides of the groove to provide a guide-way for the cans substantially equal in width to the diameter of the latter, said guiding means also serving to strip the cans from the seaming means when the table is lowered.

23. In a can heading machine, a frame, a vertically movable table on the frame, a stationary chuck plate against which the cans are clamped by the upward movement of said table, means on the frame to seam the cans, the table having a groove, a feeding means mounted to reciprocate horizontally on the table and carried thereby and operable in the groove, and guiding members on the frame upon opposite sides of the groove to provide a guide-way for the cans substantially equal in width to the diameter of the latter, said guiding means also serving to strip the cans from the seaming means when the table is lowered.

24. In a can heading machine, a frame, a vertically movable table on the frame, a stationary chuck plate against which the cans are clamped by the upward movement of said table, means on the frame to seam the cans, the table having a groove, a feeding means mounted to reciprocate horizontally on the table and carried thereby and operable in the groove, and guiding members on the frame upon opposite sides of the groove to provide a guide-way for the cans substantially equal in width to the diameter of the latter, the inner edges of the guiding members being constructed to overlap the base seams of the cans.

40. in adjusted relation to each other.

25. In a can heading machine, a frame, a vertically movable table on the frame operable to reciprocate automatically, a plurality of seaming stations on the frame above the table, and means mounted to reciprocate horizontally on the table and carried thereby for intermittently feeding the cans through the machine from one seaming station to the next during each up and down reciprocation of the table.

26. In a can heading machine, a vertically movable means for supporting the cans, a seaming means, a feeding means mounted to reciprocate horizontally on said can supporting means and carried thereby, and guide members adjustably mounted to guide cans of various diameters, the guide bars having shoulders to overlap the base seams of the cans and to strip the cans from the seaming means.

27. In a can heading machine, a vertically reciprocating table to support the cans, a stationary chuck plate against which the

cans are clamped by the upward movement of said table, a seaming means above the table, a feeding means mounted to reciprocate horizontally on said can supporting means and carried thereby, and guide bars having shoulders to overlap the base seams of the cans to draw the cans away from the seaming means when the table lowers.

28. In a can heading machine, a frame, a vertically reciprocating table mounted on the frame, a stationary chuck plate against which the cans are clamped by the upward movement of said table, a seaming means above the table, a feed bar mounted to reciprocate horizontally on and carried by the table, dogs carried by the feed bar, guide members mounted on the table and having their inner edges notched to provide shoulders adapted to overlap the base seams of the cans to guide the cans through the machine and to effect a withdrawal of the cans from the seaming means when the table is lowered and to prevent upsetting or tilting of the cans when the dogs of the feed bar operate.

29. In a machine of the character described, in combination: a frame, a table vertically reciprocal thereon; mechanism for reciprocating said table periodically and to allow the table to have a period of rest when in its uppermost position; means mounted on said table and movable bodily therewith and adapted to feed articles along said table step by step, said means including a reciprocatory member; and mechanism for reciprocating said member and adapted to impart motion thereto in one direction while the table is at rest in its uppermost position.

30. In a double seaming machine, in combination: a frame; a table slidable vertically up and down thereon; mechanism adapted to move said table and to allow the same to have a period of rest in its uppermost position; two sets of double seaming mechanisms mounted on the frame and above the table, each set including a stationary chuck plate against which the cans are adapted to be clamped by the upward movement of the table and a rotary head having seaming rollers mounted thereon; and means mounted on the table and movable bodily therewith for feeding cans step by step along the table from one seaming station to the other, said means being operated part of its cycle of operations while said table is at rest in its uppermost position, substantially as specified.

LEE C. SHARP.

It is hereby certified that in Letters Patent No. 1,082,562, granted December 30, 1913, upon the application of Lee C. Sharp, of Plattsmouth, Nebraska, for an improvement in "Can-Heading Machines," errors appear in the printed specification requiring correction as follows: Page 3, line 1, for the word "tighly" read *tightly*; page 4, line 22, for the word "frame" read *table*; same page, lines 22-23, for the word "table" read *frame*; same page, line 106, for the word "cams" read *cans*; and that the said Letters Patent should be read with these corrections therein that the same may conform to the record of the case in the Patent Office.

Signed and sealed this 20th day of January, A. D., 1914.
